(57) **CLAIM**

The ornamental design for a clipper head, as shown and described.

DESCRIPTION

FIG. 1 is a perspective view of a first embodiment of an ornamental design of a clipper head.

FIG. 2 is a front view of the first embodiment thereof.

FIG. 3 is a rear view of the first embodiment thereof.

FIG. 4 is a first side view of the first embodiment thereof.

FIG. 5 is a second side view of the first embodiment thereof.

FIG. 6 is a top view of the first embodiment thereof.

FIG. 7 is a bottom view of the first embodiment thereof.

FIG. 8 is a perspective view of a second embodiment of an ornamental design of a clipper head.

FIG. 9 is a front view of the second embodiment thereof.

FIG. 10 is a rear view of the second embodiment thereof.

FIG. 11 is a first side view of the second embodiment thereof.

FIG. 12 is a second side view of the second embodiment thereof.

FIG. 13 is a top view of the second embodiment thereof.

FIG. 14 is a bottom view of the second embodiment thereof.

FIG. 15 is a perspective view of a third embodiment of an ornamental design of a clipper head.

FIG. 16 is a front view of the third embodiment thereof.

FIG. 17 is a rear view of the third embodiment thereof.

FIG. 18 is a first side view of the third embodiment thereof.

FIG. 19 is a second side view of the third embodiment thereof.

FIG. 20 is a top view of the third embodiment thereof.

FIG. 21 is a bottom view of the third embodiment thereof.

FIG. 22 is a perspective view of an ornamental design of a clipper head.

FIG. 23 is a front view of a fourth embodiment of an ornamental design of a clipper head.

FIG. 24 is a rear view of the fourth embodiment thereof.

FIG. 25 is a first side view of the fourth embodiment thereof.

FIG. 26 is a second side view of the fourth embodiment thereof.

FIG. 27 is a top view of the fourth embodiment thereof; and,

FIG. 28 is a bottom view of the fourth embodiment thereof.

The broken lines shown in FIGS. 1-16 and FIG. 23 are included for the purpose of illustrating environmental elements only and form no part of the claimed design.
